Primary Examiner — Sandra Snapp(74) *Attorney, Agent, or Firm* — Gardere Wynne Sewell LLP(57) **CLAIM**

The ornamental design for a chair, as shown and described.

DESCRIPTION

Fig. 1 is a perspective view of a chair; *FIG. 2* is a right side view of the chair shown in *FIG. 1* the left side being a mirror image thereof; *FIG. 3* is a top view of the chair shown in *FIG. 1*; *FIG. 4* is a bottom view of the chair shown in *FIG. 1*; *FIG. 5* is a front view of the chair shown in *FIG. 1*; and, *FIG. 6* is a rear view of the chair shown in *FIG. 1*. The stippling is to show surface texture and is not a necessary part of the design.
